[57] CLAIM

The ornamental design for a above-water portion of a boat, as shown and described.

DESCRIPTION

FIG. 1 is a side elevation view of a above-water portion of a boat showing my new design, the reverse side being a mirror image thereof;

FIG. 2 is a front elevation view thereof;

FIG. 3 is a back elevation view thereof; and,

FIG. 4 is a perspective view taken from above and the rear left.

FIG. 1

FIG. 2

FIG. 3

FIG. 4
